UNITED STATES PATENT OFFICE.

MAX H. KLING, OF NEW YORK, N. Y.

DESIGN FOR A RING.

No. 38,160.

Specification for Design.

Patented Aug. 14, 1906.

Application filed June 2, 1906. Serial No. 319,969. Term of patent 3½ years.

To all whom it may concern:

Be it known that I, MAX H. KLING, a citizen of the United States, residing at the city of New York, in the county and State of New York, have invented a new, original, and ornamental Design for Rings, of which the following is a specification, reference being had to the accompanying drawings.

Figure 1 is a side elevation, Fig. 2 is a top

plan view, and Fig. 3 is an edge view, of a ring, showing my new design.

I claim—

The ornamental design for a ring, as shown.

MAX H. KLING.
